UNITED STATES PATENT OFFICE.

R. MILTON RETHERFORD, OF MUNCIE, INDIANA.

DESIGN FOR A CLUSTER-LAMP.

51,124.

Specification for Design.

Patented Aug. 7, 1917.

Application filed March 22, 1917. Serial No. 156,774. Term of patent 7 years.

To all whom it may concern:

Be it known that I, REUBIN MILTON RETHERFORD, a citizen of the United States, and a resident of Muncie, in the county of Delaware and State of Indiana, have invented a new, original, and ornamental Design for a Cluster-Lamp, of which the following is a specification, reference being had to

the accompanying drawing, forming a part thereof.

The figure is a front elevation of a cluster lamp, showing my new design.

I claim:

The ornamental design for a cluster lamp as shown.

R. MILTON RETHERFORD.
